UNITED STATES PATENT OFFICE.

FRED H. DOERR, OF GRAND RAPIDS, MICHIGAN, ASSIGNOR TO DOERR MANUFACTURING COMPANY, OF GRAND RAPIDS, MICHIGAN, A CORPORATION OF MICHIGAN.

DESIGN FOR A RECEPTACLE FOR SMOKERS' ARTICLES OR THE LIKE.

Application filed May 29, 1924. Serial No. 9,737. Term of patent 7 years.

To all whom it may concern:

Be it known that I, FRED H. DOERR, a citizen of the United States, residing at Grand Rapids, in the county of Kent and State of Michigan, have invented a new, original, and ornamental Design for a Receptacle for Smokers' Articles or the like, of which the following is a specification, reference being had to the accompanying drawing, forming a part thereof.

The figure is a perspective view of a receptacle for smokers' articles or the like showing my new design.

I claim:

The ornamental design for a receptacle for smokers' articles or the like, as shown.

FRED H. DOERR.
